HYDRAULIC WELL PUMPING MECHANISM

Louis A. Ringman, Toledo, Ohio, assignor to The National Supply Company, Pittsburgh, Pa., a corporation of Pennsylvania

Application January 30, 1940, Serial No. 316,323

3 Claims. (Cl. 121—158)

This invention relates generally to a hydraulic pump and more particularly to a hydraulic mechanism for pumping wells.

Another object of this invention is the provision of a fully hydraulically controlled pumping mechanism.

Another object is the provision of a fluid operated and controlled pumper which is fully automatic.

Another object is the provision of a fluid operated and controlled well pumper which utilizes the well load for operating the pump piston in one direction.

Another object is the provision of a fluid controlled pumping mechanism capable of being automatically operated through any one of a series of selected strokes.

Another object is the provision of a fluid controlled pumper operated by a fluid pressure.

Another object is the provision of a fluid pumping mechanism wherein the stroke and the motion of the pumper are operated by the same working fluid.

Another object is the provision of means for controlling the descending movement of the pumper piston.

Another object is the provision of means for decelerating the piston to a stop at the bottom of its stroke.

Another object is the provision of a fully hydraulic pumping mechanism which is self-contained, having no communication with the atmosphere.

Another object is the provision of a fully self-contained hydraulic pumping system capable of circulating the working liquid during the idling and downstroke periods and when excessive pressures build up within the system.

Another object is the provision of new and improved structural apparatus making up a hydraulic pumper and the method of operating the same.

Other objects and advantages appear in the following description and claims.

In the accompanying drawings a practical embodiment illustrating the principles of this invention is shown wherein:

Fig. 1 is a diagrammatic view of a hydraulic pumping mechanism showing a simplified control mechanism comprising this invention.

Fig. 2 is a view similar to that shown in Fig. 1 with the provision of additional means for obtaining different stroke lengths of the pump piston and for decelerating the movement piston at the lower end of the down stroke.

Fig. 3 is a diagrammatic view of a complete hydraulic pumping mechanism similar to that shown in Fig. 2 with the operating control mechanism housed in a single casing. The control in this instance is set at the idle position with the pump piston at the lower end of the cylinder.

Fig. 4 is a view similar to Fig. 3 illustrating the position of the controls during the upstroke of the pump piston for a selected stroke length.

Fig. 5 is a view similar to Fig. 4 illustrating the reversal of the control mechanism to check the ascent of the pump piston and to cause it to descend from the top of the selected stroke.

Fig. 6 is a view similar to Fig. 5 showing the position of the controls during the time the pump piston is descending and illustrating how its motion is retarded.

Fig. 7 is a view similar to Fig. 6 illustrating the automatic operation of the control mechanism for decelerating and finally stopping the piston at the lower end of the selected stroke just prior to its reversal, the control valve approaching the position similar to that shown in Fig. 4, thus representing a complete cycle of the operation of the pump piston.

Fig. 8 is a view similar to Fig. 3 with the controls set for moving the pump piston to the top of the cylinder without reversing the movement of the piston, thereby causing the relief valve to function due to the development of an excessive fluid pressure in the system.

Fig. 9 is a side elevation of an actual pumping unit showing the pump and reservoir connected thereto.

Fig. 10 is a diagrammatic view of a complete pneumatically operated pumping mechanism.

Fig. 11 is an enlarged sectional view of the top of the pump cylinder shown in Fig. 10.

Fig. 12 is a diagrammatic view illustrating a battery of fluid operated pumping mechanisms actuated from a common source of fluid pressure supply.

Fig. 13 shows a horizontally disposed fluid pumping mechanism arranged to operate a plurality of pumping jacks.

Referring to Fig. 1 of the drawings, 10 represents a well casing which is closed at its upper end by the well casing head 11 having a centrally disposed opening therein arranged to carry slips or other suitable means for receiving the well tubing 12 forming the pump barrel within the well. This tubing is suitably packed to prevent the escape of fluid under pressure from the well. A tubing adapter 13 is secured to the

top of the tubing 12 and is provided with one or more vents 14 for the discharge of fluid pumped from the well. This adapter is preferably made in two parts as shown, the upper part serving as a cylinder anchor for the motor cylinder 15 and having an opening therethrough to provide access to the packing glands 16 and 17. This opening may be closed by plates to keep out the dirt.

The cylinder 15 has an annular flange member 18 preferably welded to the lower end thereof for securing the same in an annular seat or shoulder 19 of the adapter. The latter is provided with a dashpot chamber 20 below the open end of the cylinder 15.

The upper end of the cylinder 15 is enclosed by the cap 21 secured by bolts to an annular flange 22 welded or otherwise fastened to the cylinder. The top of the cap is provided with the eye 23 for hoisting the pump as a unit. A shoulder 24 is provided in the bore of the cap defining a chamber thereabove.

The motor piston 25 is arranged to reciprocate within the cylinder 15 and has secured thereto the polish rod 26 which extends down through the packings held by the glands 16 and 17 and into the tubing 12 where it is fitted with a suitable pump plunger. It will be noted from the drawings that the shoulder 24 and the bottom of the dashpot chamber 20 are engaged by the piston 25, thereby determining the limiting position of the piston in the cylinder and these limits are obviously determined by the length of the cylinder 15.

The valves which control the operation of the motor piston are shown in their simplest form in Fig. 1 wherein 28 represents the pilot valve spool slidably supported in the valve chamber 29, and 30 represents the master valve spool slidably supported within the chamber 31. The pilot valve spool is urged to the left by the spring 32. The right end of the master valve spool is arranged to engage an adjustable stop 33 for controlling the speed of the piston 25 as it descends.

The source of hydraulic power in the preferred form of the apparatus disclosed is the pump 34 operated by a suitable prime mover as indicated by the motor 35. The working liquid is contained in the sump or reservoir 36 which is provided with two compartments formed by the dividing wall 37. The liquid is withdrawn from the compartment 38 and received upon its return from the system into compartment 40. Thus any foreign matter carried back to the reservoir is retained in compartment 40 by the dividing wall and may be removed through a suitable sludge opening not shown.

The liquid is withdrawn from the compartment 38 of the reservoir through the line 41 to the pump 34 where it is forced under pressure through the line 42, the relief valve 43, the line 44, to the recess 45 in the chamber 31 of the master valve 30, whence it passes to recess 46, line 47 to the dashpot 20 below the piston 25 in the cylinder 15, thereby lifting the piston 25 to actuate the polish rod on its upstroke lifting the well load.

The liquid under pressure also passes from the recess 46 through the line 48 to the recess 50 in the chamber 29 of the pilot valve where it continues through the recess 51, the line 52 to the master valve chamber 31 at the right end thereof. The pressure of the liquid thus main-

tains the master valve spool 30 in the extreme position at the left of the chamber.

Any liquid that may have been trapped between the left end of the master valve spool 30 and the chamber 31 is forced out by the movement of the spool through the line 53, to the recess 54 in the chamber 29 of the pilot valve and continues through the recess 55, the line 56, the recess 57 in the master valve chamber 31, the line 58 to the common return line 60 leading back to the compartment 40 of the reservoir 36. This circuit is of course not subjected to pressure at this time.

A line 61 connects the pressure relief valve 43 to this common return line 60 for bypassing the liquid if the pressure in the system reaches a predetermined maximum.

When the lower edge of the piston 25 has passed above the line 62 opening into the cylinder 15 adjacent its upper end, the liquid under pressure within the cylinder passes through line 62, the check valve 63, line 64 to the chamber 29 of the pilot valve at the left end thereof. The pressure on the liquid causes the pilot valve spool 28 to move to the right, compressing the spring 32 as shown in Fig. 2.

When the pilot valve spool 28 is moved to the right the liquid under pressure travels from recess 46 through line 48, recess 50 in the pilot valve chamber 29, thence to recess 54, line 53, to the master valve chamber 31 and works against the left end of the master valve spool 30, causing it to move to the right.

Any liquid trapped between the right end of the master valve spool 30 and the chamber 31 is forced out through line 52, recess 51 in the pilot valve chamber 29, thence to recess 65, line 66, recess 67 in chamber 31 to the common return line 60 and back to compartment 40 of the reservoir 36.

When the master valve spool 30 has been moved to the right as shown in Fig. 2 the liquid under pressure travels from the recess 45 in chamber 31 to recess 57 and thence through line 58 to the common return line 60. Thus the master valve spool having been reversed after the piston 25 is raised above line 62 in the cylinder 15, bypasses the liquid to the reservoir. The liquid thus circulates freely in this circuit while the piston 25 descends.

The liquid in the cylinder 15 below the piston 25 is expelled from the cylinder 15 by the weight of the piston, polish rod and parts fastened thereto plus the liquid carried thereby within the well tubing. The expelled liquid from cylinder 15 passes through the dashpot 20, line 47, recess 46 in chamber 31, to recess 67, and thence through the common return line 60 to the reservoir. The beveled surface 68 on the spool 30 throttles the liquid passing therethrough from recess 46 to recess 67. This throttling action limits the speed of the movement of the piston 25 during its downward stroke. This throttling action may be changed by the screw 33, thereby providing an external adjustment of the opening between the beveled surface 68 and the chamber 31 to regulate the speed of the down stroke of the piston 25.

The liquid being discharged from the cylinder 15 by the descending piston is also effective against the left end of the master valve spool 30 to retain it in the reversed position.

When the piston 25 descends it creates a partial vacuum thereabove.

As the upper edge of the piston 25 passes be-

low the line 70 opening into the cylinder 15 adjacent the lower end thereof, the partial vacuum above the piston draws the liquid from the left end of the pilot chamber 29 through line 64, line 71, check valve 72, line 70 to the space above the piston 25 in the cylinder 15. The spring 32 also aids in moving the liquid in this circuit. However the spring 32 could not move the pilot valve spool 28 until pressure was relieved from line 70.

After the pilot valve spool 28 has been returned to the position shown in Fig. 1, the liquid in the left end of the master valve chamber 31 is vented through the line 53, recesses 54 and 55 in the pilot valve chamber 29, line 56, recess 57 in the master valve chamber 31, line 58, the common return line 60 back to compartment 40 of the reservoir.

The pressure of the expelled liquid being discharged from the cylinder 15 by the weight of the piston 25 and the pump load is also now directed from recess 46 through line 48, recesses 50 and 51 of the pilot valve chamber 29, line 52 to the right end of the master valve chamber 31. The throttling effect created by the beveled surface 68 on the master valve spool 30 leaves sufficient pressure on the liquid forced out of the cylinder by the piston 25 to move the master valve spool 30 to the left into the position shown in Fig. 1.

This description completes a full operating cycle of the hydraulic pump. It will be noted however that when the piston 25 passed below lines 62 and 70 some of the operating liquid passed into the cylinder 15 above the piston 25. When the liquid accumulates sufficiently to spill out the line 73 with the piston at the top of its stroke it passes down through check valve 74, line 75 to the common return line 60 to the reservoir.

It will be noted that this pumping mechanism is entirely hydraulically controlled and operated. The hydraulic system is self-contained and has no communication with the atmosphere, which precludes the possibility of sand or water vapor entering the system.

The pilot valve spool serves only to control the position of the master valve spool which in turn controls the direction of the flow of liquid under pressure, thereby controlling the direction of the movement of the piston and the rate of speed that the piston descends, which is adjustable by means of the screw 33.

Referring now to Fig. 2 it will be noted that additional stroke control lines 76 and 77 have been added and they enter the cylinder 15 at positions intermediate the stroke control lines 62 and 70. Valve 78 connects either stroke control line 62 or 76 with the check valve 63 through the line 69, and valve 79 connects either stroke control line 70 or 77 with check valve 72 through the line 59. Thus by selecting the proper stroke control lines with the stroke control valves 78 and 79 the piston 25 may be made to operate in any one of four strokes such as controlled by lines 62 and 70, 62 and 71, 76 and 70 or 76 and 71. If the distance between the entry of lines 62 and 76 into cylinder 15 is different than the distance between the entry of lines 70 and 71, then each of the four strokes will be of different lengths. In this manner any number of stroke control lines may be added to produce any length of stroke desired. Again several of these stroke control lines may be added at one end of the cylinder 15 with only one stroke line at the other.

The flexibility in the application of this system is obvious.

In addition to the newly added stroke control lines, Fig. 2 also shows an added control for regulating the speed of the movement of the master valve spool 30 in traveling from right to left which action determines the deceleration of the piston 25 at the end of the down stroke by retarding the flow of the liquid from the cylinder 15 between the recesses 46 and 61. If the beveled section 68 cuts off this flow abruptly by sliding over the land section between these recesses the piston would stop suddenly, producing a shock. To avoid this shock a tapered throttle screw 80 is provided in the left end of the master valve casing to restrict the passage of the fluid therefrom. Thus the smaller the orifice the slower the movement of the spool 30 to the left resulting in gradually stopping the flow of liquid from the cylinder 15, thereby gradually decelerating and finally stopping the downward movement of the piston 25.

A small leakage hole 80' is provided in the throttle screw 80 to prevent stalling of the master valve spool in case one happened to turn the tapered screw 80 completely into the opening.

A check valve 81 is arranged to by-pass the needle throttle valve 80 to permit the master valve spool 30 to be quickly shifted to the right when the piston is at the top of its stroke and is about to reverse.

In Fig. 1 the structure is shown in its simplest form to demonstrate the principles of this invention. In Fig. 2 the stroke control and the piston decelerating mechanisms have been added to illustrate the complete invention. However in these two views the relief valve, the pilot and master valves, the stroke control valves and the various check valves have been shown as separate or individual structures. Each of these structures has been combined in Figs. 3 to 8 into a single housing 82 which in practice is secured to one side of the cylinder anchor and the line connections running to the various levels of the cylinder 15 may be made by small copper lines as illustrated in Fig. 9. The lines are enclosed in the long box or conduit 83 extending up one side of the cylinder 15 and the lines 42 and 60 connecting the pump and the reservoir with the housing 82 may be flexible hose connections to prevent vibration from being transmitted between these two parts of the mechanism. The pump and the reservoir have been combined into one housing as illustrated at 84, which is secured to the same base as the motor 35.

Referring now to Figs. 3 to 8, the stroke control valves 78 and 79 are shown as cylindrical plugs rotatably mounted in a common chamber 85 and having radial ports, disposed in angular relation to each other, and which connect with a common passage in the center of the plugs representing a portion of the lines 69 and 59 respectively as previously described relative to Fig. 2. For convenience the radial passages in the cylindrical plugs of the valves 78 and 79 are disposed at ninety degree positions. However the more control lines added may necessitate reduction of this angular spacing.

Each valve 78 and 79 is provided with a stem having an indicating dial secured thereto as shown at 86 and 87. These dials are marked as shown in Fig. 2. The numbers 62 and 76 on dial 86 indicate selection of the stroke control lines of the same number at the top of the piston 25 stroke made by turning this dial. The dial 87

likewise indicates control lines selected at the bottom of the piston stroke. In actual practice the stroke positions or lengths may be stamped thereon.

A valve drainage line 88 opens into the chamber 85 between the plugs of the valves 78 and 79 and connects with the recess 65 in the pilot valve control chamber 29 and thus passes directly to the common return line 60.

The casing 82 is also provided with a drainage line 89 connecting the right end of the pilot valve chamber 29 with the line 66, thence to the common return line 60 to avoid trapping any liquid that may leak past the last abutment of the pilot spool valve 28.

The master valve spool spring 90, which is supported on the abutment screw 33, is provided to cause leftward motion of the master valve spool in case the reversing action of the spool is so slow that the piston 25 reaches the bottom of the dashpot 20 before the spool is in position for the upward stroke, at which time the deficiency in the discharge pressure of the liquid below the piston is compensated by the force of the spring 90.

The relief valve 43 shown in detail in Figs. 3 to 8 is made spool-shape similar to the pilot and master valves. This valve is held to the left by the spring 91 which may be adjusted by the screw 92 to obtain a predetermined pressure on the spool, causing it to function as a safety device to protect the system from excessive pressures. When the pressure of the system exceeds the predetermined amount as set by the loading of the spring the liquid under pressure becomes effective against the differential piston 93 at the left of the spool 43 through the line 94 connected to the main line 42. The small differential piston 93 may be omitted if desired. The spool 43 is then moved to the right against the pressure of the spring 91 and the liquid under pressure is by-passed from the recess 95 to the recess 96, which is represented by the line 61 in Figs. 1 and 2. A drainage line 87 is provided for the right end of the spool valve 43 to prevent trapping of any liquid that may have leaked past the valve.

Excessive pressures may occur when one fails to properly set dial 86 and the piston 25 reaches the top of its stroke as indicated in Fig. 8, or at any point of the upstroke where the load of the polish rod is excessive, such as may be encountered when a well sands up.

Again referring to Fig. 3 a line 98 is shown connecting the line 47, adjacent the dashpot 20 in the adapter 13, with a radial opening in the stroke control plug valve 78 leading to the line 69, check valve 63, line 64 to the left end of the pilot valve chamber 29. This line 98 is connected only when the dial 86 is set at the idling position, during which time the pressure of the working liquid is sufficient to compress the pilot valve spring 32 but insufficient to raise the piston 25, since the master valve spool 30 is floating back and forth permitting the balance of the working liquid delivered by the pump 34 to by-pass from the recess 45 to the recess 57 and thence through the line 58 to the common return line 60. The working liquid is also effective through the recess 46 of the master valve, the line 48, the recesses 50 and 54 of the pilot valve, the line 53, the check valve 81 to the left end of the master valve chamber 31 and thus being effective to force the master valve spool to the right compressing the spring 90.

When the dials 86 and 87 are set to connect 78

lines 76 and 77 respectively as shown in Fig. 4 the pressure of the working fluid formerly effective through the line 98 on the left end of the pilot valve spool 28 is cut off by the rotation of the dial 86 and at the same time line 76 is cut into the circuit but there is no pressure in this line or above the piston 25. The spring 32 thus forces the pilot valve spool 28 to the left, pushing the working liquid out of the chamber 29, through line 64, line 71, check valve 72, line 59, stroke control valve 79, line 77 to the cylinder 15 above the piston 25.

The movement of the pilot valve spool 28 connects the left end of the master valve chamber 31 with the common return and admits the working liquid under pressure to the right end of the master valve spool 30, thereby moving it to the left. When the recess 45 is cut off from the recess 57, the pressure of the working fluid builds up sufficient force to lift the piston 25 on its upward stroke as shown in Fig. 4.

Fig. 5 shows the piston 25 after it has just cleared the selected line 76 admitting liquid under pressure to the left end of the pilot valve chamber 29 moving the pilot valve spool 28 to the right, thereby admitting liquid under pressure to the left end of the master valve chamber 31, moving the master valve spool 30 to the right while connecting the right end of the master valve chamber to the common return line 60. The illustration in Fig. 5 shows the master valve spool just about to open the by-pass between recesses 45 and 57 and close the connection between recesses 45 and 46.

Any excess liquid in the cylinder 15 above the piston 25 will at this time be drained off through the line 73, check valve 74 and on to the common return 60.

The master valve spool continues to move to the right until it reaches the position shown in Fig. 6. The working liquid is then completely by-passed to the common return 60 and the liquid from the cylinder 15 is being forced through the line 47, recess 46, past the beveled surface 68 of the valve, recess 67 to the common return 60 with the pressure thereon being effective on the left end of the master valve spool 30 to maintain it to the right in the position shown.

After the piston clears the stroke control line 77 in the cylinder 15 on its downward stroke as shown in Fig. 7 the liquid formerly trapped at the left end of the pilot valve spool 28 and holding it to the right is drawn back into the cylinder 15 through the line 77 because of the partial vacuum therein and because of the force exerted by the pilot valve spring 32.

Thus the pilot valve spool 28 moves to the left as shown in Fig. 7, thereby connecting the left end of the master valve cylinder 31 with the common return 60 and connecting the liquid discharged from the cylinder 15 to the right end of the master valve chamber 31 to aid in moving the master valve spool 30 to the left. The movement of this valve toward the left end of the chamber is of course impeded by the restricted flow past the needle valve 80, which action gradually cuts off the flow of the liquid past the beveled surface 68 on the master valve spool. When this flow is completely cut off the working liquid from the pump is about to be admitted from the recess 45 to the recess 46 as shown in Fig. 7, at which time the pumped liquid under pressure will cause the piston to again ascend within the cylinder 15.

This description thus completes the action of

the control apparatus for a full cycle of the operation of the piston 25.

Gages 100 and 101 may be placed at different parts of the system to determine the pressure. Gage 100 is placed adjacent the discharge of the pump 34 in the line 42 which registers a positive pressure at all times. The gage 101 placed at the top of the cylinder 15 in line 73 must be capable of reading negative or sub-atmospheric pressures as well as pressures thereabove.

Referring now to the pneumatic pumping mechanism shown in Fig. 10, it will be noted that the structure is the same as the hydraulic mechanism with the exception of the master valve 30 and the source of fluid pressure supply. The master valve 30 of the pneumatic control system is provided with a continuous land section 110 which prevents communication between the recess 45 containing fluid under pressure and the recess 57 leading through line 58 to the discharge line 60. This continuous land section prevents the escape of energized fluid from the source of supply while the piston 25 is moving downwardly. In the hydraulic system the fluid may circulate but in a pneumatic system the fluid energy must not be needlessly wasted.

This pumping mechanism is arranged to be operated from any suitable source of gas under pressure. This source of supply may be obtained from a high pressure gas well or a compressor station which produces a head pressure on either gas or air. The compressor pumping station is preferably provided with the type of apparatus usually employed for such purposes, including an accumulator. The fluid under pressure is conveyed to the control mechanism through the conduit 111 to the pressure regulator 112 whence it travels through the pipe 42 to the control mechanism.

The disposition of the pneumatic working fluid depends upon the character of fluid employed. If the source of supply is a high pressure gas it is discharged through the line 60 to the valve 113 where it may pass to the lower pressure line 114. This line may be a common discharge line from a plurality of similar pumping units. Again the exhaust gas may be returned through the line 115 to the compressor station for recompression. If a combustible gas is used it may be piped to an accumulator where it is finally discharged to a furnace engine or other similar use. The line 116 connected to the valve 113 is arranged to discharge the pneumatic fluid to the atmosphere.

Shut-off valves 117 and 118 are provided in the lines 42 and 60, respectively, to permit the pumping unit to be disconnected from the fluid system.

The pressure relief valve 43 is provided with a communication 119 between the extreme end faces to equalize the pressure acting thereon. This structure is required when the exhaust fluid pressure is discharged into a fluid pressure line. The pressure acting on the right face of the valve is also effective on the left face of the valve. The communicating passageway 119 thus nullifies the effectiveness of the pressure in the fluid discharge line 60 and the valve 43 is actuated by the small differential piston 93 in the same manner described above.

In pneumatically operated pumping mechanism a pop valve 120 may be provided in the upper end of the cylinder 15 in the same position as the gauge 101 described above. This valve is purely a pneumatic safety measure.

With these changes the pumping apparatus

has been converted from a hydraulically operated mechanism to a pneumatically operated mechanism. The control valves and the pump piston operate in the same manner, since their movement is in response to the pressure of the fluid.

In either the pneumatic or hydraulic mechanisms the pilot valve spring 32 may be replaced by the differential piston 121 which is actuated by fluid under pressure effective through the line 122 which is connected to the line 47. The left end of the pilot valve 28 and the right end of the differential piston 121 are subjected to the same fluid pressure when the piston passes the selected upper control line 62 or 76 at the end of its upward stroke, but the pilot valve 28 will move to the right because the area of the left end of the pilot valve is greater than that of the differential piston. The pressure in the cylinder 15 under the piston as it descends maintains the check valve 72 in its closed position and the pressure effective against the left end of the pilot valve maintains it to the right until the piston 25 passes below the selected lower control line 70 or 71, at which time the low pressure above the piston discharges the pressure from the left end of the pilot valve 28. The pressure effective from the line 47 through the line 122 again forces the pilot valve to the left, which action again reverses the master valve and the piston ascends in its pumping stroke. Thus the same pumping action is obtained through the pilot control valve by the use of the differential piston 121 in place of the spring 32.

Referring to Figs. 10 and 11, the piston 25 is provided with a hollow tubular extension 123 arranged to pass up through the packing 124 in the head 125. The packing may be compressed by the gland member 126. The piston extension 123 is longer than the cylinder 15 and protrudes above the head 125 when the piston is in its lowermost position. The upper end of the extension is provided with a small bore for receiving the polish rod 26. A packing 127 and a gland member 128 are provided for sealing the polish rod as it passes through the piston extension. A polish rod clamp 129 is secured to the rod above the piston for locking it thereto. A casing, not shown, may be slid over the piston extension and fastened to the head 125 to keep the dirt and weather off the piston surface.

The purpose of this piston extension is to permit the operator to raise or lower the pump plunger in the well and thus properly space it from the bottom thereof to obtain the most effective operation of the well pump. Again the well pump is made more readily accessible with the polish rod extending above the apparatus.

In Fig. 12 a battery of fluid operated pumping mechanisms are shown connected to a common source of fluid pressure supply as indicated by the line 130 and the return or exhaust line 131. These pumping units may be operated pneumatically or hydraulically from a common source of supply. The valves 117 and 118 together with the unions permit the removal of any one unit from the system without disturbing the operation of the other units.

In Fig. 13 the fluid pumping mechanism is supported in the horizontal position by the base casting 132. A similar casting may be used for supporting the other end of the cylinder 15. In this instance the polish rod 26 is replaced by a pull rod 133 which extends to the depending arms 75 of the pump jacks 134. The load on the polish

rods 26, which are supported from the outer ends of the walking beams of the pump jacks, is balanced to provide the proper gravity return force for moving the piston 25 of the pumping mechanism to the left, which is the same as returning it to the bottom of the cylinder 15 in the other views. The piston in each instance is thus biased by the gravitational forces of the pumping mechanism and load. Thus it is obvious that this fluid motor may be employed for cotton tampers, baling presses, stoker rams, or any other type of mechanism requiring a continuous reciprocating cycle of operation as long as some means is provided to bias or reverse the movement of the piston on the non-load stroke.

I claim:

1. In a fluid operated pumping mechanism, the combination of a cylinder, a piston working in the cylinder and biased to move toward one end of the latter, a master valve arranged when in one position to admit fluid under pressure to one end of the cylinder to move the piston toward the other end and when in another position to relieve the fluid pressure from the cylinder to permit the piston to return, a pilot valve arranged to control the operation of the master valve, two sets of control lines, one set entering the cylinder adjacent one end and the other adjacent the other end for regulating the stroke of the piston, check valve mechanism, and unitary means for selectively connecting one control line through said check valve mechanism from each set with the pilot valve for operating the same, the pressure of the fluid being effective through a selected control line at one end to actuate the pilot valve in one direction and the relief of said pressure through a selected control line at the other end being effective to actuate the pilot valve in the other direction and accordingly control the stroke of the piston.

2. In apparatus for controlling the operation of a piston biased to move toward one end of a cylinder, the combination of a fluid pressure-actuated master valve arranged when in one position to admit fluid under pressure to move the piston toward the other end of the cylinder and when in another position to relieve the fluid pressure and permit the piston to return, an operat-

ing line connecting the master valve to the first mentioned end of the cylinder, a fluid pressure-actuated pilot valve arranged to control the operation of the master valve, a manually operated valve for selecting the limit of the stroke of the piston at the second mentioned end of the cylinder, an idling control line connecting the operating line with said selector valve, two control lines forming independent connections between said selector valve and longitudinally spaced ports adjacent the second mentioned end of the cylinder, a second manually operated valve for selecting the limit of the stroke of the piston at the first mentioned end of the cylinder, two control lines forming independent connections between said second selector valve and longitudinally spaced ports adjacent the first mentioned end of the cylinder, a passageway connecting each of said selector valves with a common connection to the pilot valve, a check valve admitting flow from the first selector valve to the pilot valve and a check valve permitting flow from the pilot valve to the second selector valve, the pressure of the fluid in the cylinder being effective through a selected control line of the first selector valve to actuate the pilot valve in one direction and the relief of said pressure being effective through a selected control line of the second selector valve to actuate the pilot valve in the other direction.

3. In a hydraulic pumping mechanism the combination of a cylinder, a piston working in said cylinder and biased to move toward one end of the latter, fluid pressure-operated valvular means for admitting fluid under pressure to and discharging it from the said end of the cylinder to be effective on one side of the piston, two sets of control lines connected with said cylinder, the connections of the individual lines of each set being in spaced relation, two passages connected to said valvular means and having oppositely working check valves therein, each set of control lines having one of said passages operatively associated therewith, and means for selectively connecting one of the control lines of a set with the corresponding passage for varying the length and the position of either end of the piston stroke in the cylinder.

LOUIS A. RINGMAN.
